UNITED STATES PATENT OFFICE.

HIRAM H. HUNTINGTON, OF RICHMOND, INDIANA, ASSIGNOR TO THE AMERICAN
SEEDING MACHINE COMPANY, OF SPRINGFIELD, OHIO, A CORPORATION OF OHIO.

HANGER FOR FURROW-OPENER DRAG-BARS.

1,147,324.

Specification of Letters Patent.

Patented July 20, 1915.

Application filed April 26, 1915. Serial No. 23,880.

To all whom it may concern:

Be it known that I, HIRAM H. HUNTINGTON, a citizen of the United States, residing at Richmond, in the county of Wayne and

5 State of Indiana, have invented certain new and useful Improvements in Hangers for Furrow-Opener Drag-Bars, of which the following is a specification.

This invention relates to improvements in 10 hangers for drag-bars of furrow openers for grain drills.

The object of the invention is to provide a hanger which will be simple, strong, effective and economical in manufacture.

15 In the accompanying drawings: Figure 1 is a perspective view of a portion of a grain drill frame and one of its drag-bars showing my improved hanger applied thereto. Fig. 2 is a rear elevation of the hanger, the dotted lines illustrating the same before being bent into shape.

Like parts are represented by similar characters of reference in the several views.

In the said drawings, 1 represents a portion 25 of the front angle-iron rail of the frame of a grain drill.

2 and 3 represent the bifurcated forward portion of one of the drag bars. The hanger which connects the drag-bar to the frame is 30 formed from steel, cut and bent to shape, and consists of a main portion 4, side ears 5 and 6 and a flange 7 along its lower edge between the ears 5 and 6. The portion 4 is secured to the vertical portion of the frame by 35 the bolts 9 which pass through the perforations 8 and corresponding perforations (not shown) in the frame. The bifurcated end of the drag bar straddles the hanger and is pivoted on the pin 11 which extends through 40 perforations 10 in the ears 5 and 6 and also through perforations in the drag-bar and is held in position by cotter pins 12 at its respective ends.

In forming the hanger, the metal is cut 45 at the points 13, the portion 7 given a right angled bend, and the portions 5 and 6 bent at right angles against the ends of the flange

7. The main portion 4 is cut away at the top so as to allow the ears 5 and 6 to project above the same.

By the construction described it will be seen that a simple, cheap, and strong hanger is provided, the flange 7 between the ears 5 and 6 providing a rigid brace for said ears against the strain of draft of the drag-bar. 50 It will also be seen that the perforations in the ears 5 and 6 which receive the pivot pin 11 are immediately below the flange 7 so that said flange will be located relatively to the ears at the point of greatest strain 60 thereon. Also by having the ears project above the top of the main portion, said ears may be brought in close contact with the under side of the horizontal portion of the frame 1, thus removing the strain of draft 65 to a large extent from the bolts 9.

Having thus described my invention, I claim,

1. A hanger for drag bars consisting of a main portion arranged to be secured to the 70 frame of the machine, ears at the respective ends of said main portion bent at right-angles thereto and a right-angled flange on one edge of said main portion interposed between said ears.

2. In a hanger for drag bars, the combination, with an angle-iron frame, of a hanger composed of a main portion secured to the vertical part of said frame, integrally formed ears at the respective ends of said 80 main portion bent at right-angles thereto, the upper edges of said ears lying in close proximity to the under side of the horizontal part of said frame, an integrally formed flange on the lower edge of said main portion extending at an angle thereto between said ears, and means for pivotally connecting the bifurcated ends of a drag bar to the outer sides of said ears.

3. In a hanger for drag-bars, the combination, with an angle-iron frame having an upper horizontal portion and a forward vertical portion, of a hanger composed of a main vertical portion secured to the vertical

part of said frame, rearwardly extending ears at the respective ends of said main portion, the upper edges of said ears standing in close proximity to the under side of the horizontal part of said frame, a rearwardly extending flange on one edge of said main portion interposed between said ears, and means for pivotally connecting the bifur-

cated end of a drag-bar to the outsides of
10 said ears.

In testimony whereof, I have hereunto set
my hand this 23rd day of April 1915.

HIRAM H. HUNTINGTON.
